UNITED STATES PATENT OFFICE.

HERBERT J. GWYER, OF YONKERS, NEW YORK.

REFRIGERATOR-LINING CONSTRUCTION.

Application filed May 25, 1921. Serial No. 472,537.

To all whom it may concern:

Be it known that I, HERBERT J. GWYER, a citizen of the United States of America, residing at Yonkers, Westchester County, New York, have invented a new and useful Refrigerator-Lining Construction, of which the following is a specification.

My invention relates to a refrigerator construction and particularly to a unitary lining for the same.

It is an object of the invention to provide a cheap, serviceable lining.

It is a further object to so form the unitary lining as to provide novel means for holding the same in a cabinet.

It is a further object to so form the lining as to provide very smooth joints which will be well suited to receive a porcelain covering.

Other objects and features of invention will be apparent as the specification proceeds.

In the preferred form of my invention a single sheet is formed to provide the back and two sides or ends, and separate sheets form the top and bottom. The front is preferably left open to provide access to the interior through the usual refrigerator doors. The top and bottom lining sections are secured to the back and ends, preferably by providing flanges at the abutting portions, and then securing the flanges together to form a unitary lining. At the four front edges of the lining flanges are preferably provided and projecting flanges are also preferably provided around the top and bottom edges of the unitary lining. A cabinet to receive my unitary lining is so formed as to provide recesses to receive the flanges above mentioned for securing the unitary lining in place.

In the drawings, which are merely for illustrative purposes, a preferred form is shown.

Figure 1 is a partially diagrammatic, perspective view of a refrigerator construction embodying features of my invention, parts being broken away to expose interior construction;

Fig. 2 is a fragmentary perspective view of one corner post and a top or bottom frame;

Fig. 3 is a fragmentary vertical sectional view of the construction shown in Fig. 1;

Fig. 4 is a horizontal sectional view of the unitary lining, parts being broken out;

Fig. 5 is a fragmentary detail of one corner of the unitary lining; and

Fig. 6 is a perspective view of a shelf support.

In said illustrative drawings the cabinet is formed of sections. The two front corner posts 5, 6 are secured together at the top and bottom by means of top and bottom tie rails, such as 7. The rear corner posts, such as 8, may be similarly secured together, and panel boards are secured in place between the posts.

The top and bottom sections of the cabinet are preferably substantial duplicates of each other and include frames composed of end sections 9, 9 and front and back sections 10, 11. The corner posts and the framing members of the top and bottom units are preferably of substantially the same cross section and sections are clearly shown out in Fig. 2.

The end panel members preferably comprise frames composed of members, such as 12, 12, and these frames interfit with the top and bottom units and with the corner posts, as is clearly shown in Figs. 1 and 3. As shown particularly in Fig. 3, the outside panel board 13 is simply slid into place between the corner posts, and the top and bottom units serve to hold the panel board in place.

The parts of the cabinet may be held together by any suitable means, but I prefer to use the rod holding construction such as shown in my co-pending application, Serial No. 383,346, filed May 22, 1920; wherein rods pass longitudinally through the corner posts and anchor the top and bottom units together for holding the cabinet in assembled form.

The unitary lining for the cabinet comprises top and bottom, back and side lining sections, the back lining section 15 being preferably formed integral with the end sections 16. At the front of the end lining sections there are preferably formed flanges 17, which fit between the corner posts and the end panel members, as is clearly shown in Fig. 1. Around the top and bottom of the back and end lining sections flanges 18 are provided, and the top and bottom lining sections are formed with corresponding flanges 19 abutting the flanges on the back and side sections. In the specific form shown, one of the flanges is doubled back upon itself, as at 20, and receives the other flange between the two sections 18, 20. The

flanges are secured together in any suitable manner, as by indenting or spot welding the flanges together, as indicated at 21. It is obvious that the flanges could be otherwise secured together, but it is preferable, for the sake of cheapness, to secure it together only at spaced intervals. If desired, one of the flanges at the corners may be formed to engage the surface of the other lining member, as shown at 22. The flange would, of course, be removed at the corner from the member which is engaged by the flange 22.

As is shown in Fig. 1, the top and bottom lining sections are provided with flanges 23 fitting between the cabinet top and bottom and the tie rails. In the specific form shown the top and bottom lining sections are dished or pan shaped and the flanges 23 are substantially parallel to the main body of the top and bottom sections.

In assembling my unitary lining in a cabinet of the special form shown, the lining is first placed on the bottom unit with the lower flanges in the recesses in the bottom provided therefor. The bottom of the dished lining preferably rests upon one of the panel boards in the cabinet bottom. The end units of the cabinet are next set in place on the bottom with the lower flanges on the lining in the recesses as shown in Figs. 1 and 3. The front and back units of the cabinet are then set in place on the bottom unit and serve to hold the front and rear flanges of the lining to the bottom of the cabinet, and the vertical flanges 17 are held between the ends and the front of the cabinet. The cabinet top is then put in place and the flanges at the upper end of the lining are held between the top and the abutting side units as shown in Figs. 1 and 3. The top and bottom cabinet members are then secured together to hold all the parts in assembled relation. It will be seen that by assembling the unitary lining as just described, the latter will be securely held in place against movement in any direction.

An ice compartment 25 is provided in the refrigerator and is preferably of the removable type as described in my co-pending application, Serial No. 474,373, filed June 2, 1921.

In order to support shelves in the food compartment, I employ a bar 26 having a hook 27 at the upper end which passes through an aperture in the lining, and the bottom of the bar 26 may likewise be provided with a projection or hook 28 passing through a correspondingly placed aperture in the lining. The rod is bent at one or more places intermediate its ends to provide shelf supports 29-29.

It will be seen that I have provided a unitary lining which will be exceedingly cheap to manufacture and which will be

very serviceable when in use. The seams or joints between the sections are smooth upon the inside thus providing a lining well adapted to receive a porcelain or other coating. The dished top and bottom of the lining give a finished, smooth appearance and reduce to a minimum the danger of having liquid on the bottom pass through the seams or joints. The assembling of such a lining in a cabinet is a simple matter and much time will be saved by the employment of this unitary lining.

While I have described in great detail one illustrative form of my invention, I wish it to be understood that various modifications and changes may be made within the scope of the claims appended hereto.

What I claim is:—

1. In a refrigerator construction, a unitary lining open at the front, outwardly projecting flanges adjacent the top and bottom of said lining, angular flanges at two sides of the open front, said projecting flanges being adapted to fit between the top and bottom respectively and the sides of a cabinet, and said angular flanges at the open front being adapted to fit between the front and two of the sides of the cabinet.

2. In a refrigerator construction, a unitary lining comprising back and side sections, some of said sections having angularly outwardly projecting flanges at the top and bottom, a top lining section, a bottom lining section, said top and bottom lining sections being rigidly secured to the flanges aforesaid, said flanges being adapted to fit between the top and bottom respectively and the sides of a cabinet.

3. In a refrigerator construction, a unitary lining comprising back and side sections, a dished top lining section, a dished bottom lining section, flanges on the vertical and horizontal edges of side sections and projecting angularly outwardly therefrom, flanges on the top and bottom sections projecting outwardly in a direction substantially parallel to the body of the top and bottom sections, said flanges being adapted to fit between the front, top, bottom and two sides of a cabinet.

4. In a refrigerator construction, a unitary lining comprising back and side sections, a top section, a bottom section, said top and bottom sections having flanges interengaging with parts of the back and side sections, said flanges and parts being permanently united at spaced points.

5. In a refrigerator construction, a unitary lining comprising back and side sections, and top and bottom sections, said top and bottom sections and said back and side sections having interengaging overlapping flanges for securing the top and bottom sections to the back and side sections aforesaid.

6. In a cabinet construction, a unitary lin-

ing comprising back, side, top and bottom sections secured together to form a unit open at the front, a cabinet for said unitary lining and having a narrow recess adjacent the 5 top, an outwardly projecting horizontal flange on said unitary lining and fitting in said recess in the cabinet for positioning the unitary lining vertically in the cabinet.

7. In a cabinet construction, a unitary lining comprising back, side, top and bottom sections secured together to form a unit open at the front, a cabinet for said unitary lining and having a narrow recess adjacent the bottom, an outwardly projecting horizontal 10 flange on said unitary lining and fitting in

said recess in the cabinet for positioning the unitary lining vertically in the cabinet.

8. In a cabinet construction, a cabinet having a removable front, a unitary lining for said cabinet comprising back and side sections, and top and bottom sections secured to said back and side sections, said side sections having flanges directed outwardly and extending beyond the outside of said side sections, said flanges fitting between the removable cabinet front and the adjacent sides for positioning the unitary lining in the cabinet. 20 25

HERBERT J. GWYER.
